(57) **CLAIM**

I claim the ornamental design for a vacuum cleaner, as shown and described.

DESCRIPTION

FIG. 1 is a first perspective view of a vacuum cleaner showing my new design;

FIG. 2 is a second perspective view of the vacuum cleaner of FIG. 1, viewed in another aspect;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a perspective view of dust bin of the vacuum cleaner showing my new design; the dust bin being shown separately for ease of illustration;

FIG. 10 is another perspective view thereof;

FIG. 11 is a front view thereof;

FIG. 12 is a rear view thereof;

FIG. 13 is a left view thereof;

FIG. 14 is a right view thereof;

FIG. 15 is a top view thereof;

FIG. 16 is a bottom view thereof;

FIG. 17 is a perspective view of main part of the vacuum cleaner shown separately for ease of illustration;

FIG. 18 is another perspective view thereof;

FIG. 19 is a front view thereof;

FIG. 20 is a rear view thereof;

FIG. 21 is a left view thereof;

FIG. 22 is a right view thereof;

FIG. 23 is a top view thereof;

FIG. 24 is a bottom view thereof; and,

FIG. 25 is an exploded view of the vacuum cleaner of FIG. 1 thereof.

The broken lines depict portions of the vacuum cleaner in which the design is embodied that form no part of the claimed design.
